[57] CLAIM

The ornamental design for a self latching device, as shown and described.

DESCRIPTION

FIG. 1 is a top, front, and left side perspective view of a self latching device showing our new design;

FIG. 2 is a front elevational view thereof;

FIG. 3 is a top plan view thereof;

FIG. 4 is a bottom plan view thereof;

FIG. 5 is a right side elevational view thereof;

FIG. 6 is a rear elevational view thereof;

FIG. 7 is a left side elevational view thereof;

FIG. 8 is an enlarged top, front, and left side perspective view of the retaining member thereof;

FIG. 9 is an enlarged front elevational view of the retaining member thereof;

FIG. 10 is an enlarged top plan view of the retaining member thereof;

FIG. 11 is an enlarged bottom plan view of the retaining member thereof;

FIG. 12 is an enlarged left side elevational view of the retaining member thereof;

FIG. 13 is an enlarged rear elevational view of the retaining member thereof;

FIG. 14 is an enlarged right side elevational view of the retaining member thereof;

FIG. 15 is a top, front, and left side perspective view of the latching member thereof;

FIG. 16 is a front elevational view of the latching member thereof;

FIG. 17 is a top plan view of the latching member thereof;

FIG. 18 is a bottom plan view of the latching member thereof;

FIG. 19 is a right side elevational view of the latching member thereof;

FIG. 20 is a rear elevational view of the latching member thereof; and,

FIG. 21 is a left side elevational view of the latching member thereof.

Portions of the assembly are shown omitted in the views for clarity of illustration.
